UNITED STATES PATENT OFFICE.

JOHN C. TALLMAN, OF BRIDGEPORT, CONNECTICUT, ASSIGNOR TO WARNER BROTHERS, OF SAME PLACE.

CORSET.

SPECIFICATION forming part of Letters Patent No. 279,041, dated June 5, 1883.

Application filed March 13, 1883. (No model.)

To all whom it may concern:

Be it known that I, JOHN C. TALLMAN, a citizen of the United States, and a resident of Bridgeport, in the county of Fairfield and 5 State of Connecticut, have invented certain new and useful Improvements in Corsets, of which the following is a specification.

My invention consists of the mode of constructing corsets hereinafter fully set forth, 10 whereby I am able to make corsets the body portions of which are of but one thickness of material and to insert the bones or stiffeners in the pockets and press the same between flat plates before the sections of the corsets are 15 united.

Heretofore in the construction of corsets having but a single thickness of cloth in the body portion it has been customary to make the body portion out of properly-formed sections, sewed together at the edges with the 20 seams outside, which seams are then covered with strips sewed to the outside of the corset, the said strips being stitched upon parallel lines to form with the body portion pockets 25 in which to insert the stiffeners. This is very objectionable, because it is difficult to stitch the overlying strips neatly to the irregular body portion. The seams beneath the said strips cause protuberances, which impair the 30 finish of the article, while it is impossible to bone the corset until the parts are all sewed together, which prevents the effective application of pressure so as to set and solidify the boning material and impart a neat finish to the 35 surface. I overcome these objections by constructing the corset in the manner illustrated in the accompanying drawings, in which—

Figure 1 illustrates the forms of the sections constituting part of a body of a corset. Fig. 40 2 is an edge view, showing the relative positions of the sections and overlying strips; Fig. 3, the same, showing three sections as arranged prior to being united; and Fig. 4, the same, showing the sections connected together.

45 A series of sections, A. A, consisting each of a single thickness of cloth, are cut of any suitable forms, so that when united edge to edge they will constitute a body of the proper shape. Upon each of said sections is laid a strip, *a*, 50 narrower than the section, one edge, *i*, coincid-

ing with the edge *e* of the section below it, and the two are stitched together upon the lines *e'* to form a series of pockets for the reception of the bones or stiffeners *b*, the edges *i i'* of the strips *a* extending some distance beyond the 55 line of stitching at each side, as shown in Fig. 2. The stiffeners are then inserted, (provided they were not inserted during the act of stitching,) and the separate sections thus boned are placed upon a flat plate and there subjected to heat 60 and pressure in such manner as to set the stiffeners in the pockets and impart a smooth polished finish to the surfaces of the material. The edges *i i'* of the sections *a* and the edge *e* of the body-sections are then folded inward, 65 and the unfolded edge *f* of each body-section is inserted between the folded edges *i e* of the next section, as shown in Fig. 3, and the folded edges are stitched upon the lines *s s*, as shown in Fig. 4, thereby neatly connecting the finished sections together and completing the 70 body of the corset. By this means I simplify and cheapen the construction of the corset. I am enabled to compress the boned section upon flat surfaces, and I avoid the necessity of forming exposed seams, while the corset thus produced is neater in appearance and has a better 75 finish than those made in the ordinary manner.

It will of course be apparent that this mode of manufacture may be pursued in making corsets portions of which are double and other portions of single thickness, and that the strips *a*, of any desired form, may be put upon the inside instead of the outside of the body-sections.

If desired, the edges *i'* of the overlying sections may be stitched prior to uniting the sections.

I do not disclaim any patentable features herein shown and not specifically claimed, reserving the same for future applications for Letters Patent.

I claim—

1. The improvement in manufacture of corsets herein described, consisting in making sections of single thickness of cloth shaped to constitute the body portion, stitching a strip narrower than the section upon each section to form pockets, and leaving loose edges at each side of the section, boning and pressing each 95 100

section, and then inserting the single thickness of the edge of each body-section between the turned-in edges of the body-section and strip of the adjacent section and stitching the same 5 together, substantially as set forth.

2. The combination, in a corset, of a body composed of sections of one thickness of cloth, each section being partly overlaid by a covering-strip stitched thereto on parallel lines, one 10 edge of which strip coincides with one edge of

the section, the opposite edge of said section being stitched between the edges of the next section and strip, substantially as set forth.

In testimony whereof I have signed my name to this specification in the presence of two sub- 15 scribing witnesses.

J. C. TALLMAN.
